UNITED STATES PATENT OFFICE.

ALBERT S. LANG, OF CUDAHY, WISCONSIN.

BURNER PROTECTOR.

Application filed May 5, 1928. Serial No. 275,525.

This invention relates to improvements in burner protectors.

Liquids which are being cooked over an open stove burner are frequently left unattended for a considerable period of time. During this interval, they often boil over, and extinguish the flame beneath. This allows the gas to escape from the burner, and to circulate throughout the room. Children or others, who may be near by, may become asphyxiated before they are aware of the danger.

It is one of the objects of this invention to obviate this hazard, and to provide a burner protector which will permit the burner to function in its normal manner, and which will at the same time render it impossible for the flame to be accidentally extinguished.

It is a further object of this invention to provide a burner protector which permits sufficient air to circulate between the top of the burner and the protector to allow the flame to burn properly.

It is a further object of this invention to provide a burner protector which is simple in construction, inexpensive to manufacture, and well adapted for the purpose described.

With the above and other objects in view, the invention consists of the improved burner protector and all its parts and combinations as set forth in the claims, and all equivalents thereof.

In the accompanying drawing, in which the same reference characters designate the same parts in all of the views:

Fig. 1 is a top view of the protector in attachment with a burner, part of the burner being broken away;

Fig. 2 is a sectional view taken on line 2-2 of Fig. 1;

Fig. 3 is a sectional view taken on the line 3-3 of Fig. 1;

Fig. 4 is a fragmentary view of the burner and protector showing an end view of one of the burner wings; and

Fig. 5 is a sectional view through one of the wings of the burner showing a modified form of protector in attachment therewith.

Referring to the drawing, the numeral 8 designates a burner of a standard type which is formed with a central body portion 9 having an opening 10 therein, and having a plurality of wings 11 extending radially out-

wardly. The top of the burner has a plurality of perforations 12 for the discharge of the gas.

The improved protector 13 comprises a sheet of metal of the same shape as the top of the burner, having downwardly bent edges 14 which overlap the edges of the burner. The central portion of the protector has an opening 15 to correspond with the opening 10 in the burner. The edges of the opening 15 are also downwardly flanged as at 16. The opening 15 in the protector is somewhat smaller than the opening 10 in the burner to provide a space 17 for air to enter.

All of the downwardly flanged edge portions are corrugated as at 18. These corrugations permit air to enter underneath the protector, and also permit an outlet for the flames from the burner. The edge corrugations extend slightly over the top of the burner, so that the protector will rest on the corrugations and will not fit tightly on the top of the burner, but will leave a small space 19 as shown in Fig. 3.

The upper surface of the protector is formed with radially extending corrugations 20 which extend from the opening 15 to the outer edges. These corrugations are above the perforations 12 of the burner and allow a supply of air to enter from the center opening 15.

In the modified form shown in Fig. 5, the edge corrugations 18 extend considerably further over the edges, and the protector is supported by these corrugations and held in a raised position. The top of the protector is formed with an inverted cup-shaped portion 21 which leaves a large space 22 between the top of the burner and the protector. By having this large space, it is unnecessary to have the corrugations 20 used in the principal form.

It is to be understood that the particular shape of the protector may be varied to fit burners of different types and shapes, the main features of the invention residing in the provision of a protector which will properly cover the burner and still allow ample air to enter to permit the burner to function properly.

To use the device, it is placed on the burner as indicated, and the gas is turned on. The latter will emanate from the sides

through side corrugations, and may be ignited with the cover in place. The flames will rise from all of the edges of the protector and will be divided up and spread out 5 so as to render it very efficient for cooking. The flames will of course be burning underneath the protector also, so that if a liquid boils over it will not reach these inner flames and hence cannot extinguish the burner. 10 Furthermore, if a food such as a cereal boils over, the protector will prevent clogging of the burner perforations.

From the foregoing description it may be seen that the improved burner protector is 15 very simple in construction and is well adapted for the purpose described.

What I claim is:

1. The combination with a burner having fuel outlet perforations therein of a protector therefor comprising a sheet of material covering said perforations so as to protect flames issuing therefrom being extinguished by overflowing material and having portions spaced from said perforations, and 20 having downwardly flanged corrugated edges overlapping the edges of the burner, providing spaces through which air may enter to the spaces above the fuel perforations to maintain the burner in ignited condition.

2. The combination with a burner having fuel outlet perforations therein of a protector therefor comprising a sheet of material covering said perforations so as to protect flames issuing therefrom from being extinguished by overflowing material and having portions spaced from said perforations, and having downwardly flanged vertically corrugated edges overlapping the 25 edges of the burner, providing spaces through which air may enter to the spaces above the fuel perforations to maintain the burner in ignited condition.

3. The combination with a star-shaped burner having fuel outlet perforations therein of a protector therefor comprising a star-

shaped sheet of material covering said top and having portions spaced therefrom.

4. The combination with a burner having fuel outlet perforations therein of a protector therefor comprising a sheet of material of substantially the same shape as the top of the burner covering said top so as to protect flames issuing therefrom from being extinguished by overflowing material and 50 having portions spaced from said top, and having downwardly flanged corrugated edges overlapping the edges of the burner, providing spaces through which air may enter to the spaces above the burner top to 55 maintain the burner in ignited condition.

5. The combination with a burner having fuel outlet perforations therein and having a central opening, of a protector therefor comprising a sheet of material of substantially the same shape as the top of the burner, and having a central opening of smaller diameter than the central opening of the burner, said sheet of material covering the top of the burner so as to protect 60 flames issuing therefrom from being extinguished by overflowing material and having portions spaced from said top and having downwardly flanged corrugated edge portions overlapping the edges of the burner, providing 65 spaces through which air may enter to the spaces above the burner to maintain the burner in ignited condition.

6. A burner protector comprising a sheet of material of substantially the same shape 70 as a burner adapted to completely cover the burner to protect flames issuing therefrom from being extinguished by overflowing material, and having downwardly flanged, corrugated edge portions and upwardly raised top portions to permit air to 75 enter between the top of the burner and the protector to maintain the burner in ignited condition.

In testimony whereof I affix my signature.

ALBERT S. LANG.
